US0D1047706S

(12) **United States Design Patent** (10) **Patent No.:** **US D1,047,706 S**
(45) **Date of Patent:** ** *Oct. 22, 2024

(54) **SMART HYGIENE DEVICE**

(71) Applicant: **Hygiene IQ, LLC**, Los Angeles, CA (US)

(72) Inventors: **Sean M. Podvent**, Los Angeles, CA (US); **Richard Adams**, Los Angeles, CA (US); **Aleksandar Bradic**, Palo Alto, CA (US); **Vojislav Antonic**, Pasadena, CA (US)

(73) Assignee: **Hygiene IQ, LLC**, Los Angeles, CA (US)

(*) Notice: This patent is subject to a terminal disclaimer.

(**) Term: **15 Years**

(21) Appl. No.: **29/758,933**

(22) Filed: **Nov. 19, 2020**

(57) **CLAIM**

The ornamental design for a smart hygiene device, as shown and described.

DESCRIPTION

A portion of the disclosure of this patent document contains material which is subject to copyright protection. The copyright owner has no objection to the reproduction by anyone of the patent document or the patent disclosure as it appears in the Patent and Trademark Office patent file or records, but otherwise reserves all copyright rights.

FIG. 1 is a front view of a smart hygiene device showing our new design;

FIG. 2 is another front view thereof;

FIG. 3 is another front view thereof;

FIG. 4 is another front view thereof;

FIG. 5 is another front view thereof;

FIG. 6 is another front view thereof;

FIG. 7 is a front view of a smart hygiene device showing our new design;

FIG. 8 is another front view thereof;

FIG. 9 is another front view thereof;

FIG. 10 is another front view thereof;

FIG. 11 is another front view thereof;

FIG. 12 is another front view thereof;

(Continued)

FIG. 13 is a front view of a smart hygiene device showing our new design;

FIG. 14 is another front view thereof;

FIG. 15 is another front view thereof;

FIG. 16 is another front view thereof;

FIG. 17 is another front view thereof; and,

FIG. 18 is another front view thereof.

The broken lines in the drawings show portions of the smart hygiene device that form no part of the claimed design.
